C. L. SMITH

ORCHARD LADDER

Filed Aug. 16, 1926

Patented Sept. 6, 1927.

1,641,906

UNITED STATES PATENT OFFICE.

CARL L. SMITH, OF HOOD RIVER, OREGON.

ORCHARD LADDER.

Application filed August 16, 1926. Serial No. 129,434.

My present invention pertains to step ladders for orchard use in which a single stile is employed.

The general object of my invention is the provision of a step ladder of the kind indicated in which the steps are strongly supported and in which the steps are equipped with guards for the feet of a user, and this without materially increasing the cost of the step ladder.

Other objects and practical advantages of the invention will be fully understood from the following description and claims when the same are read in connection with the drawings, accompanying and forming part of the specification, in which:—

Figure 1 is a front elevation of a step ladder constituting the preferred embodiment of my invention.

Figure 2 is a side elevation of the same. Figure 3 is a horizontal section, on an enlarged scale, taken on the plane indicated by the line 3—3 of Figure 1, looking downwardly,

Figure 4 is a horizontal section on an enlarged scale taken on the plane indicated by the line 4—4 of Figure 2 looking downwardly.

Figure 5 is a detail elevation illustrative of the prop connection, said view being taken from a view point at the right of Figure 2.

Figures 6 and 7 are detail views of the stile per se as hereinafter explicitly referred to.

Similar numerals of reference designate corresponding parts in all the views of the drawing.

Among other elements, my novel ladder comprises a stile 1, divergent braces 2 fixed at their upper ends to the stile 1 and disposed at opposite sides of said stile 1 and a back strip 3 disposed at right angles to the stile 1 and which like the stile 1 and the braces 2 is preferably formed of wood. The said strip 3 is fixed to the back of the stile 1 and extends laterally beyond the sides of the stile 1 and is provided in its lateral portions at intermediate points in its length with mortises 4 and is also provided in the upper end of its laterally extended portions with mortises 5, the mortises 4 being clearly brought out in Figures 3 and 6, and the mortises 5 being made clear by Figures 4 and 7.

Interposed between the divergent braces

2 is a cross brace 6 and below the side cross brace 6 is a cross rod 7 and reinforcing strips 8, the cross rod 7 being secured at its ends in the divergent braces 2, and the reinforcing strips 8 being connected to the inner sides of the braces 2 and being arranged immediately under the cross brace 6 and the rod 7.

At 9 are combined steps and braces, preferably of wood, arranged at opposite sides of the stile 1 and supported at their inner ends in mortises 4 in the strip 3 and having their outer ends opposed to the divergent braces 2. It will also be understood at this point that the rod 10 is extended through the divergent braces 2, the steps 9 and stile 1, and is secured in position for the strong connection of the steps 9 to the braces 2 and the stile 1.

I prefer to have my novel ladder comprise four pairs of steps 11, one of the said pairs being arranged between the divergent braces 2 and the other three pairs of steps 11 arranged above the said divergent braces 2. All of the said steps 11 are preferably formed of wood, and each step 11 has its inner end opposed to the stile 1 and supported in a mortise 4 in the strip 3. It will also be noted that each pair of steps 11 are connected together and to the stile 1 by a bolt 12, headed at 13, and that guard plates 14 are secured in working relation to the steps 11 by the bolts 12. In this connection it will be noted that each guard plate 14 is interposed between a head 13 of the bolt 12 and the outer end of one step 11 and is extended above the surface of the step 11 so as to effectively prevent the foot of a user from slipping off the step 11. This will be appreciated as an important advantage of my invention when it is taken in consideration that the guards 14 in addition to the purpose stated serve to reinforce and strengthen the outer ends of the steps 11.

The stile 1 extends a considerable distance above the uppermost steps 11^x of the ladder, so that a convenient hand hold is afforded for a considerable distance above the upper steps 11^x. The said upper steps 11^x are of much greater width than the steps 11, compare in this connection Figures 3 and 4, and the said upper steps 11^x are arranged at opposite sides of the stile 1 and are supported in the uppermost mortises 5 of the strip 3. It will also be noted that a block 15, Figure 4, is interposed between the steps 11^x. The

said steps 11* are reinforced by metallic rods 16 having heads 17 at their ends. Headed rods 18 and 19 are also passed through the steps 11* for reinforcing purposes, and the rod 19 is also passed through the interposed block 15 and is used as a pintle in the connection of straps 20 through the medium of which a prop 21 is connected with the uppermost steps 11*. The block 15 hereinbefore alluded to is formed by the upper end of the prop 21, Figure 5, and hence it will be appreciated that the prop 21 is directly connected in hinged manner with the steps 11* and is also connected in hinged manner with said steps 11* through the medium of the straps 20 which manifestly contribute to the strength and durability of the ladder.

A chain or other flexible cable 22 is preferably interposed between and connected to the prop 21 and the strip 3, Figure 2, said cable 22 serving to limit outward movement of the prop 21.

It will also be understood from Figure 2 that the prop 21 is provided at its inner side and at its lower end with a reinforcing block 23 designed to lessen the liability of the lower end of the prop sinking into soft ground.

It will be appreciated from the foregoing that my novel single stile ladder is at once simple and inexpensive in construction, light in weight, safe in use and strong and durable in construction; also, that the ladder is susceptible of being conveniently moved from point to point in an orchard or other place where the ladder is used.

I have specifically described the construction and relative arrangement of the parts comprised in the present and preferred embodiment of my invention in order to impart a full, clear and exact understanding of the said embodiment. I do not desire,

however, to be understood as limiting myself to the precise structure shown and described, my invention being defined by my appended claims within the scope of which structural changes may be made without departures from my invention.

Having thus described the invention, what I claim is:—

1. A single stile ladder having a stile and divergent braces fixed thereto and also having a back strip fixed to the back of the stile and extending at right angles to the stile laterally beyond the sides of the stile and having in its laterally extending portions, mortises, steps corresponding in width to the combined stile and back strip and arranged at opposite sides of and against the stile and having their inner ends seated and supported in said mortises of said back strip, and headed bolts extending through and connecting the steps and the stile; each of the said steps being of wood and being provided at its outer end with a guard plate opposed to said end and extending above the upper surface of the step, and the said guard being arranged upon the bolt and between one head thereof and the opposed end of the step.

2. The combination in a ladder, of a stile, a back strip fixed to the back of the stile and extending at right angles to the stile laterally beyond the side of the stile and having in its laterally extended portion mortises, steps arranged at the side of and against the stile and having ends seated and supported in said mortises of said back strip; said steps corresponding in width to the combined stile and back strip, and means connecting the steps and the stile.

In testimony whereof I affix my signature.

CARL L. SMITH.
